UNITED STATES PATENT OFFICE.

JAMES R. SHAFFER, OF HUNTINGTON, INDIANA.

PICKET-WIRING MACHINE.

SPECIFICATION forming part of Letters Patent No. 451,581, dated May 5, 1891.

Application filed February 24, 1891. Serial No. 382,680. (No model.)

To all whom it may concern:

Be it known that I, JAMES R. SHAFFER, a citizen of the United States, residing at Huntington, in the county of Huntington and State 5 of Indiana, have invented new and useful Improvements in Wire-Fence-Making Machines, of which the following is a specification.

My invention relates to an improvement in wire-fence-making machines; and it consists 10 in the construction and arrangement of parts hereinafter described, and definitely pointed out in the claims.

The object of my invention is to provide a simple, efficient, inexpensive, and convenient 15 device for twisting the wires in uniting the pickets of a fence. This object I attain by the construction illustrated in the accompanying drawings, wherein like letters of reference indicate like parts in the several views, 20 and in which—

Figure 1 represents a perspective view of a portion of a fence in process of construction, showing my device in operative position to 25 twist the wires between the pickets. Fig. 2 is a front elevation of the device. Fig. 3 is a sectional view of the device on the line $x-x$ of Fig. 2. Fig. 4 is a detail perspective of the ratchet-wheel and the pawl, and Fig. 5 is a cross-section through the same.

30 In the drawings, A and A' represent two holders constructed, preferably, in the form of pliers, the jaws a a' being semicircular in form and constructed with channels a² on their inner faces. The ends of these jaws are curved outwardly in opposite directions to 35 form a mouth through which the wires are passed.

B represents a circular disk located between the jaws, its periphery resting in the 40 channel in the jaws, and in which it is permitted a rotary movement in either direction. This disk has a radial groove or slot c therein, adapted to register with the space between the ends of the jaws, which slot extends in 45 ward to a point slightly beyond the axis of the disk. This slot c is intended to receive the fence-wires, so that the wires will be twisted by the rotation of the disk. The outer or upper face of this disk is provided 50 with a series of ratchet-teeth c', placed at intervals an equal distance apart.

The center of the outer or upper face of the

disk C is provided with a laterally-projecting hub D, having a radial slot d therein and two recessed bolt-holes, a portion of which are 55 enlarged at their lower ends, formed in opposite sides thereof. On the top of this hub is placed a circular plate E, corresponding to the shape of the hub. This plate is held in position by bolts F, passing through apertures in the disk and the bolt-holes in the hub, and is made yielding by the interposition of rubber gaskets or springs placed between the head of the bolts and plate in the 60 enlargement of the bolt-holes. This plate is 65 constructed to project beyond the hub and form a bearing for the upper edge of a circular pawl G, fitted around the hub, the ends of this pawl having gaging-teeth g, which engage with the ratchet-teeth on the disk. It 70 is permitted to slide over the teeth in its backward movement by means of the yielding plate bearing on its upper edge.

To the sides of the pawl G, at a point between its ends, is secured a yoke H, its ends 75 extending out beyond the jaws and provided with T-heads h, adapted to engage and rest against the adjacent pickets of the fence.

I is a spring located on the handle for normally holding the jaws apart. 80

The operation of my device is as follows: The pickets are placed in position between the two binding-wires, which are placed parallel. The device is placed between the pickets, the wire being passed through the mouth 85 between the ends of the jaws into the radial slot in the disk until the T-heads come in contact with the pickets, thereby holding the ratchet stationary. The handles are then raised and the jaws forced together. Pressure 90 is then placed on the handles, which act as a lever, forcing the disk around relative to the ratchet. The jaws are then loosened, leaving the disk in this position, and afterward raised and closed to again engage the 95 disk, which operation is continued until the two wires are twisted together and the pickets secured in place. The operation is thus continued throughout the construction of the fence, it being understood that only one picket 100 at a time is permanently secured in place.

I am aware that many minor changes can be made in the arrangement and construction of the parts of my device and substituted

for those herein shown and described without in the least departing from the nature and principle of my invention. Having thus described my invention, what I claim as new, and desire to secure by Letters Patent, is—

1. A picket-wiring fence-machine consisting of a holder in the form of pliers having its two jaws channelled on their inner faces, a revolving ratchet-disk between the jaws, formed with a radial slot therein, and a pawl engaging said disk and having extensions for engaging the pickets of a fence, substantially as described.
15. 2. In a picket-wiring fence-machine, the combination, with two compressible channelled jaws, of a rotary disk between the jaws, having a radial groove therein, a ratchet engaging the disk, and means for rotating the disk, substantially as described.
20. 3. In a picket-wiring fence-machine, the

combination, with two compressible jaws, of a revolving ratchet-disk between the jaws, having a radial slot therein, a spring for normally holding the jaws apart, and a ratchet 25 for rotating the disk, having extensions for engaging the pickets of a fence, substantially as described.

4. The combination, with two compressible channelled jaws, of a slotted ratchet-disk between the jaws, a hub on the disk, a plate on the hub, a yielding connection between the plate and the disk, and a circular pawl below the disk, having T-head extensions for engaging the pickets of a fence, substantially 35 as described.

In testimony whereof I affix my signature in the presence of two witnesses.

JAMES R. SHAFFER.
